UNITED STATES PATENT OFFICE.

HARRY C. ADAM, OF ST. LOUIS, MISSOURI.

CRYSTAL DETECTOR.

Application filed March 12, 1923. Serial No. 624,521.

This invention relates to devices that are used for receiving wireless signals, and particularly, receiving devices of the kind that are commonly referred to as "crystal detectors".

One type of crystal detector that is now in general use consists of a crystal of galena or other mineral having rectifying properties, a metallic holder for said crystal to 10 which one side of an electric circuit is connected and a contact connected to the other side of said circuit and adapted to be arranged in engagement with the crystal so as to complete the electric circuit which the 15 detector controls. Owing to the fact that the crystal consists of a piece of mineral composed of particles that have rectifying properties and particles that are non-rectifying, it is necessary to use a contact that 20 has a very fine terminal or end and construct said contact in such a way that it can be adjusted or moved over the crystal until the terminal of the contact touches a rectifying particle of the crystal, the contact 25 usually being formed from a piece of fine wire connected to a finger piece that can be manipulated to adjust the contact relatively to the crystal. In using a crystal detector of the kind referred to it is often difficult 30 to set the contact at a point on the crystal where the device will function properly, and another objectionable characteristic of such a detector is that a slight jar or jolt is apt to change the relationship between the 35 terminal of the contact and the crystal, thus necessitating readjustment of the contact.

I have discovered that if a crystal or piece of mineral having such properties as to permit of its use in a detector for receiving 40 wireless signals is crushed or divided into small particles and one of said particles that has rectifying properties is then arranged between two contacts or electrodes of materially greater area than said particles, that 45 a detector will be produced which has not the objectionable characteristic of requiring delicate adjustment of one part of the device to insure the device functioning properly.

50 The particular shape, size and design of the contacts or electrodes are immaterial and the kind and size of the piece of rectifying substance that is interposed between said contacts is also immaterial, but a very 55 satisfactory crystal detector can be produced by arranging a small piece of rectify-

ing material, even as small as the head of a pin or smaller, between contacts or electrodes of materially greater area that are arranged in the electric circuit of an apparatus for receiving wireless signals, said piece of rectifying material being in contact with said electrodes and supported by the same.

60 Figure 1 of the drawings is a vertical sectional view of a crystal detector constructed in accordance with my invention.

Figure 2 is an elevational view, illustrating another form of my invention.

Figure 3 is a vertical sectional view, taken 70 on the line 3—3 of Figure 2; and

Figure 4 is a side elevational view of the resilient element of the detector shown in Figures 2 and 3.

Referring to Figure 1 of the drawings, 75 A designates a base piece formed preferably of insulating material, B designates two contacts or electrodes secured to said base piece and adapted to be arranged in the electric circuit of an apparatus for receiving wireless signals, and C designates a small particle of material having rectifying properties that is arranged between the contacts B in engagement with and supported by the same. Each of the contacts 80 B preferably consists of a flat strip of metal that has some resiliency and said contacts are mounted on the base piece A in such a way that the upper end portions of same will be in opposed relation and will exert 85 a slight pressure on the rectifying substance C that is interposed between them. If desired, the contacts B can be arranged vertically on the base piece A and positioned 90 at opposite sides of a cup D that is arranged 95 underneath the upper end portions of the contacts between which the rectifying particle C is positioned, thus forming a detector composed of two contacts or electrical conductors of relatively great area that are 100 held in spaced relation by a particle of rectifying material of materially less area than said contacts, and a device D arranged in such a position that it will receive the rectifying particle C in the event it becomes 105 displaced from its normal operative position between the contacts B. The contacts B are connected to the supporting base A by fastening devices 1 that can also be used 110 for connecting said contacts to the opposite sides of the electric circuit, in which the detector is arranged.

The detector shown in Figures 2, 3 and 4 embodies the same desirable characteristics as the detector shown in Figure 1 and is composed of two contacts or electrodes E 5 and F of relatively great area and a small particle of material G having rectifying properties, interposed between said contacts in engagement with the same and retained in position by a slight resilient pressure exerted on said particle G by one of said contacts. The contact E consists of a rigid disk-shaped metal member provided at its lower end with a bracket 2 that is connected to a base or supporting structure H by a fastening device 3 that can also be used as a binding post for one side of the circuit in which the detector is arranged, and the contact F preferably consists of a limber member formed of material that is a good 20 electrical conductor and provided with a flexible or resilient central portion 4^a that is disposed oppositely to the boss 4 on the contact E. The particular shape or design of the member F is immaterial, but I prefer 25 to form said member from a disk-shaped element provided with a spiral slot z, as shown in Figure 4, thereby producing a contact or conducting member that has a flexible or resilient central portion 4^a. The rectifying substance G is positioned between the boss 4 of the member E and the resilient central portion 4^a of the member F, as shown in 30 Figure 3. The member F is protected by a housing I or cover which is retained in position by fastening devices 5 which pass through said cover and member and are screwed into the disk-shaped member E. The member F is insulated from the member E by an annular insulator 6 arranged between said parts at the peripheral edge of the member F and a soft annular insulator 7 that surrounds the boss 4 on the inner side of the member E, the portions of the fastening device 5 that pass through the cover 45 I and member F being surrounded by insulators 8, so as to insulate said fastening devices from said cover and member F. In the form of my invention herein shown the other side of the electric circuit in which 50 the detector is arranged is connected to the cover I and member F by a screw or binding post 9 that is screwed into the cover I and member F, as shown in Figure 3. In a detector of the construction above described 55 the rectifying particle G holds the central

portion 4^a of the member F spaced away from the boss 4 on the member E and the soft annular insulator 7 that surrounds the boss 4 serves as a means to prevent said rectifying particle from becoming displaced or moved out of engagement with the two contacts of the detector. 60

While I have herein illustrated two different forms of my invention, I wish it to be understood that my broad idea consists of a so-called crystal detector for receiving wireless signals that is composed of two contacts or electrodes of relatively great area and a particle of rectifying material of materially less area than the opposed faces of said contacts interposed between the same in engagement therewith and supported by said contacts. 70

Having thus described my invention, what I claim as new and desire to secure by Letters Patent is:

1. A crystal detector composed of two substantially disk-shaped conducting members arranged in parallel relation, one of said members being rigid and the other member being relatively limber and having a flexible or resilient central portion, a small-sized particle of material having rectifying properties interposed between said resilient portion and the opposed part of the rigid member, an insulating means positioned between said members, and a housing arranged in overlapping relation with said limber member and secured to said rigid member. 90

2. A crystal detector composed of a rigid conducting member of substantially disk form arranged in an upright position and provided at its center with a boss, a co-operating limber member arranged at one side of said rigid member in parallel relation with same and provided with a substantially spiral slot so as to form a flexible or resilient central portion that is disposed oppositely to the boss on the rigid member, a small-sized particle of material having rectifying properties interposed between said boss and resilient central portion, means arranged at the center and at the outer edges of said members for insulating said members from each other, and a disk-shaped cover extending over said limber member and secured to said rigid member. 100 105
